UNITED STATES PATENT OFFICE.

HERBERT J. DAY, OF DES PLAINES, ILLINOIS.

SICKLE.

Application filed May 21, 1923. Serial No. 640,326.

To all whom it may concern:

Be it known that I, HERBERT J. DAY, a citizen of the United States, residing at Des Plaines, in the county of Cook and State of Illinois, have invented certain new and useful Improvements in Sickles, of which the following is a specification.

This invention relates to a sickle having a backing wherein are mounted a plurality of aligned blades which may be individually or collectively replaced when desired; and more particularly it is concerned with an improved and inexpensive construction of means for securing in place the several blades which may consist of ordinary discards from safety razors.

An exemplification of this invention is shown in the accompanying drawing wherein—

20 Figure 1 is a side elevation of the device; Fig. 2 is a front elevation thereof; and Fig. 3 is a top plan view thereof.

The present article comprises three major parts, a backing A in which are secured the 25 several blades B with the aid of a spring clamp C. The backing may be formed of any desired material, such as wood, having a proper cross sectional form, as, for example, that which is suggested in Fig. 3.

30 A slot 5 such as would be produced by a saw cut is formed lengthwise of the backing extending from one end 6 for a desired distance toward the other 7 where a suitable handle configuration is provided. The two 35 sections of the backing lying on opposite sides of the slot may be spread, expanded, or separated to a slight extent as permitted by the material used.

In a backing of this general description 40 are secured a number of blades B each of which may have the general form and construction that is common with present day safety razors of standard design. Each of these blades is inserted in the slot 5, the 45 depth of which is such as to cause one cutting edge 8 to remain protruded exteriorly of the backing. By preference the slot wherein these blades are accommodated is of such width that the blades will be received 50 with a relatively close fit, requiring, perhaps, a slight spreading of the backing sec-

tions for this purpose. In this manner the blades will each remain of their own accord due, in part, to the friction or pressure exerted by the engaging faces of the backing. 55

The assembly of the several blades within the handle is followed by fitting thereover a spring clip C. This is of a generally tubular form with a longitudinal cut in its walls sufficiently wide to provide engaging edges 9 60 which grip opposite sides of the backing, as best shown in Fig. 3. By preference the walls of the backing are tapered as at 10 from the opening of the slot 5, the diverging walls thus provided being engaged by the 65 clamping edges of the clip. Likewise the rear side of the backing may be rounded, as at 11, to conform to the proximate surface of the clamp, as shown.

A sickle constructed in accordance with 70 the preceding description will present a plurality of blades in end to end relation each secured within the longitudinal slot of the backing. One of the cutting edges of each blade will remain protruded exteriorly of 75 the backing for a sufficient distance to perform a cutting operation when required so to do. In addition the walls of the backing adjacent the cutting edge of each blade are converged sufficiently to not interfere with 80 the material which is to be attacked by the instrument. It is to be noted, furthermore, that the engagement of the backing with the blades is augmented by the pressure afforded by the clip. This clip may be slid by 85 an endwise movement to its position, and will remain indefinitely in place due, in part, to the engagement of its edges 9 with the diverging walls of the backing. For 90 these reasons, a sickle having the characteristics mentioned will be dependable in use. Should it become necessary or desirable at any time to reverse the blades, or substitute others, this may be readily accomplished by removing the clip and then withdrawing the 95 several blades, or altering their positions within the backing.

I claim:

In a sickle, the combination of a fibrous 100 backing having its walls exteriorly tapered toward a point, there being formed longitudinally in the backing a slot which opens

between the tapered walls thereof whereby a pair of spaced sections are provided in the backing, a plurality of blades recessed within the slot between the two sections but protruded therefrom for a slight distance, and a spring clip in the form of a slotted tube adapted to engage with the tapered sides of

the backing to exert pressure thereupon whereby the blades are also gripped with pressure, substantially as described.

HERBERT J. DAY.
